CLAIM

The ornamental design for a lid for a culture vessel, as shown and described.

DESCRIPTION

FIG. 1 is a front view of a lid for a culture vessel of the present invention.

FIG. 2 is a rear view of the lid for a culture vessel of FIG. 1.

FIG. 3 is a top plan view of the lid for a culture vessel of FIG. 1.

FIG. 4 is a bottom view of the lid for a culture vessel of FIG. 1.

FIG. 5 is a right side view of the lid for a culture vessel of FIG. 1.

FIG. 6 is a left side view of the lid for a culture vessel of FIG. 1.

FIG. 7 is a perspective view of the lid for a culture vessel of FIG. 1.

FIG. 8 is a sectional view of the lid for a culture vessel of FIG. 1, taken along the line 8-8 of FIG. 1; and,

FIG. 9 is an enlarged sectional view of the lid for a culture vessel of FIG. 1, taken along the line 9-9 of FIG. 8.

The features shown in dotted lines depict environmental subject matter only and form no part of the claimed design. The broken lines in the drawing adjacent to a shaded area of the lid for the culture vessel depict the boundary of the claim. It is understood that the claim extends to the boundary.
